UNITED STATES PATENT OFFICE.

ROBERT W. SCOTT, OF LEEDS POINT, NEW JERSEY, ASSIGNOR OF ONE-HALF TO LOUIS N. D. WILLIAMS, OF OGONTZ, PENNSYLVANIA.

KNITTED WEB.

No. 830,375.

Specification of Letters Patent.

Patented Sept. 4, 1906.

Application filed October 19, 1905. Serial No. 283,515.

To all whom it may concern:

Be it known that I, ROBERT W. SCOTT, a citizen of the United States, residing in Leeds Point, New Jersey, have invented certain Improvements in Knitted Webs, of which the following is a specification.

My invention relates to that class of knitted fabrics which are partly ribbed and partly plain and in which there is an excess of wales in the ribbed fabric as compared with the number of wales in the plain fabric, the object of my invention being to produce a machine-knit fabric of this character in which the change from rib-stitch to plain stitch can be readily effected by manipulation of the needles and without stopping the machine or requiring the intervention of an attendant, the invention being therefore especially adapted for use in the manufacture of hosiery upon automatic knitting-machines.

In the accompanying drawings, Figures 1, 2, 3, and 4 represent, on a much exaggerated scale, various fabrics made in accordance with my invention. Fig. 5 is a diagram showing an arrangement of needles such as may be used in a machine for producing the character of fabric shown in Figs. 1, 2, and 4. Fig. 6 is a diagram representing an arrangement of needles such as may be used in a machine for producing fabric of the character shown in Fig. 3. Fig. 7 is a vertical sectional view of sufficient of a knitting-machine to illustrate the method of transfer of a stitch from a dial-needle to a cylinder-needle. Fig. 8 is a similar view, but showing the parts in different relations to each other; and Fig. 9 is a view of a special form of cylinder-needle which is sometimes employed.

In Figs. 1 to 4 of the drawings, *a* represents plain-stitch wales which extend throughout both the ribbed and plain webs; *b b'* represent rib-stitch wales, and *d* represents plain-stitch wales resulting from the union of a pair of rib-stitch wales *b b'*. Plain-stitch wales may be described as those having all of their stitches drawn to the face of the web and rib-stitch wales as those having all of their stitches drawn to the back of the web.

In the fabric shown in Fig. 1, the wales *b* have rib-strokes in courses 1, 2, and 3, but change to plain stitches in course 4, and in the latter course rib-strokes of wales *b'* are doubled with the plain stitches which supplant

the rib-strokes in wales *b*, all of the stitches in course 5 being plain stitches. In the fabric shown in Fig. 2 the stitches of the rib-wales *b b'* are united in course 3, a single rib-stitch being drawn through these doubled stitches in course 4 and these single rib-strokes being then transformed into plain wale-strokes in course 5. Both of these fabrics are instances of "two-and-two" rib webs transformed to plain web, a "two-and-two" ribbed web meaning one in which pairs of plain wales alternate with pairs of rib wales in the ribbed portion of the fabric. In Fig. 3, however, I have shown an instance of a change from a one-and-one ribbed web to a plain web, "one-and-one" ribbed web meaning web in which single, plain, and rib wales alternate with each other. In this fabric the rib-stitch wales *b* change to plain-stitch wales in course 3, and in said course 3 the stitches of the rib-wales *b b'* are carried across a plain-stitch wale *a* and are doubled with the stitches which supplant the rib-wales *b*, all of the stitches drawn in course 4 being plain stitches.

In the needle-diagrams shown in Figs. 5 and 6, *x* represents cylinder-needles which are always in action, *w* represents cylinder-needles which in knitting ribbed fabric are out of action, but are in action, together with the needles *x*, in knitting plain fabric, and *y y'* represent dial-needles which are in action during the knitting of ribbed web, but which transfer their stitches to the normally inactive cylinder-needles *w* in effecting the change from ribbed web to plain web and are then put out of action.

In effecting the production of fabric such as shown in Fig. 1 the stitches are first transferred from the dial-needles *y*, Fig. 5, to the cylinder-needles *w*, and said dial-needles *y* are then put out of action. After the formation of a course of stitches 4, Fig. 1, upon the cylinder-needles, including the needles *w*, and upon the dial-needles *y'* the stitches are transferred from said dial-needles *y'* to the needles *w*, and said dial-needles *y'* are then put out of action.

In producing the fabric shown in Fig. 2 a stitch is first transferred from a dial-needle *y'* to a dial-needle *y* by shogging said needle *y'* laterally past the adjoining needle *y* and then projecting the latter so that it can enter the stitch upon the needle *y'*. The needle *y* having engaged the stitch is retracted and

the dial-needle y' is put out of action, and after the production of a course of stitches upon the cylinder-needles x and dial-needles y the stitches are transferred from said dial-needles y to the previously-inactive cylinder-needles w , the dial-needles y are put out of action, and plain fabric is produced upon the cylinder-needles x and w .

The production of the fabric shown in Fig. 3 is substantially the same as that of the fabric shown in Fig. 1—that is to say, the stitches are first transferred from the dial-needles y , Fig. 6, to the cylinder-needles w —the dial-needles y are put out of action, a course of 15 stitches is knitted upon the cylinder needles x w and upon the dial-needles y' , and the stitches upon the dial-needles y' are then transferred to the cylinder-needles w and the dial-needles y are put out of action.

20 After the first transfer of stitches from the needles y to the needles w in either machine and the retirement of said needles y more than one course may, if desired, be knitted upon the cylinder-needles x w and dial-needles y' before transferring the stitches from the latter to the needles w and putting them out of action, and in like manner any desired number of courses of stitches may be formed upon the cylinder-needles x and dial-needles y' after transferring the stitches from dial-needles y' to said needles y and putting needles y' out of action before transferring the stitches from the needles y onto the previously-inactive cylinder-needles w , or, on the 25 other hand, a complete transfer of stitches may be made in one and the same course, as shown, for instance, in Fig. 4. In the fabric shown in the latter figure stitches of both rib-wales b b' are united in course 3, and a single 30 plain stitch is drawn through these united stitches in course 4.

In carrying out my invention various forms of machine may be employed; but in Figs. 7 and 8 I have shown sufficient of the 45 elements of one form of machine which has proven effective in practice to impart a proper understanding of the method of manipulating the needles to effect a transfer of stitches from one to another. In these views 10 represents part of a needle-cylinder, and 11 part of a dial on the inside of the cylinder. The dial-needles y y' are carried by the lower ends of jacks 12, pivotally mounted upon a fixed ring 13, and having their upper ends acted 50 upon by cams carried by a cam-plate 14, this plate having two sets of cams, one for acting upon the jacks for causing operation of the dial-needles for ordinary knitting and another set for causing abnormal projection of the 55 dial-needles, so as to carry them outwardly beyond the cylinder-needles, as shown. This has the effect of drawing or stretching the web, so as to dispose rib-strokes over the cylinder-needles, as shown in Fig. 7, so that said 60 dial-needles may be projected and caused

to enter said rib-strokes, as also shown in said Fig. 7, it being understood that the dial-needles before being projected in the manner described have, if such movement is necessary, been shogged or moved laterally into 70 line with the cylinder-needles which are to receive the stitches therefrom, so that said cylinder-needles are free to rise into said stitches. If the cylinder-needle engages directly with the stitch upon the dial-needle, a 75 slight further shogging or lateral movement of either cylinder or dial needle can then be effected, so as to insure engagement of the cylinder-needle with the dial-needle stitch when said dial-needle is retracted so as to 80 cast off its stitch, as shown in Fig. 8; but if the abnormal projection of the dial-needle has been to such an extent as to draw a 85 precedently-formed rib-stitch over the cylinder-needle such lateral shogging of either 90 cylinder or dial needle preparatory to the retraction of the dial-needle will not be necessary, since the slackening of said precedently-formed stitch on the retraction of the dial-needle will cause it to engage with the projected cylinder-needle. In like manner a 95 dial-needle may after having been abnormally projected be shogged laterally, so as to carry it slightly beyond an adjoining dial-needle, and the latter may be projected so as 100 to engage the neighboring dial-stitch and after engagement with the latter can be withdrawn, so as to permit of the shogging back of the transfer-needle and the retraction of the same to cast its stitch.

In any of the machines used for producing my improved fabric the cylinder is, by preference, cut or grooved so as to present a uniform gage, whereby a correspondingly uniform gage of plain web is insured, the spreading of the wales shown in the various views of the drawings not being apparent in the finished fabric, as the contractile power of the ribbed web causes its surface wales to lie 105 as closely together as those of the plain web.

My improved fabric can be knitted without arresting the operation of the machine and by the use of a continuous thread, it being understood that the knitting-cams and the transfer-cams are disposed at points so 115 remote from each other that the knitting operation can be going forward upon certain of the needles of the machine while stitches are being transferred from and to other needles of the machine at a point more or less remote 120 from the knitting-point.

My invention is not limited to a web composed of a single continuous yarn, nor does the term "continuous" necessarily imply unbroken continuity, as yarns of different 125 color or character may be used in different portions of the web so long as the meeting ends of said yarns overlap or provide for a continuous feed of yarn to needles of one and the same machine.

When the transfer of stitches is to be effected from cylinder-needles to dial-needles, said cylinder-needles will have butts or projections—such, for instance, as shown 5 at *w* in Fig. 9—in order that when abnormally projected they will stretch the plain-stitch wales to such an extent as to permit the dial-needles to enter and engage the same.

10 A fabric produced in accordance with my invention is distinct from one in which the stitches of a ribbed web are run onto a lesser number of needles in a plain-knitting machine in the usual way, for in the ordinary 15 method of running on the doubling of two stitches of the ribbed web onto a single needle of the plain-knitting machine is a haphazard operation, and such doublings are consequently matters of chance and are 20 therefore distributed without any regard to uniformity of spacing throughout the web, whereas in a fabric produced in accordance with my invention the single wales of the plain web produced by doubling wales of the 25 ribbed web are disposed at uniformly-spaced intervals throughout the web. A further distinction between my improved fabric and one made by running on in the usual manner is that in my fabric there is a continuous 30 yarn common to both webs, whereas in the ordinary fabric the plain web is necessarily knitted with a yarn independent of that of which the ribbed web is composed.

Having thus described my invention, I 35 claim and desire to secure by Letters Patent—

1. A machine-knit fabric, partly ribbed and partly plain, and having in the ribbed web wales in excess of those in the plain web, standing wales in both webs, and a plurality 40 of wales of one web continued as a single wale of the other web at uniformly-spaced intervals throughout the web.

2. A machine-knit fabric, partly ribbed and partly plain, and having a continuous 45 yarn common to both webs and having also in the ribbed web wales in excess of those in the plain web, standing wales in both webs, and a plurality of wales of one web continued as a single wale of the other web. 50

3. A machine-knit fabric, partly ribbed and partly plain, and having in the ribbed web wales in excess of those in the plain web, standing wales in both webs, and a plurality 55 of wales of one web independently interknitted with, and continued as a single wale of the other web.

4. A machine-knit fabric, partly ribbed and partly plain, and having a continuous 60 yarn common to both webs and having also in the ribbed web wales in excess of those in the plain web, standing wales in both webs, and a plurality of wales of one web independently interknitted with and continued as a single wale of the other web. 65

In testimony whereof I have signed my name to this specification in the presence of two subscribing witnesses.

ROBERT W. SCOTT.
